ARTIFICIAL TOOTH
Winthrop C. Whittemore, Port Washington,
N. Y., assignor to The Dentists' Supply Com-
pany of New York, a corporation of New York

Application October 13, 1930, Serial No. 488,297
Renewed June 27, 1934

2 Claims. (Cl. 32—9)

It has been customary in artificial teeth to employ two anchoring pins projecting from the lingual side of the tooth body, the same providing spaced extending means of support by means of which the tooth is secured to the vulcanite plate, with the result that the tooth when assembled in the denture is firmly held against displacement or rotation.

In practice, it is only feasible to employ two anchoring pins where there is sufficient width of the tooth to permit the attachment of the anchoring pins directly or through anchors embedded in the porcelain body into which the pins are soldered. In those cases where the artificial tooth must be made narrow or in small sizes, there is not sufficient width to permit the employment of two pins in the customary manner, and I have found that a single round pin, if relied upon for insuring a firm attachment to the plate, does not provide sufficient rigidity to prevent the rotary displacement of the tooth during the building up of the denture preliminary to final vulcanization or even after the completion of the making of the denture where heavy strain is put upon the tooth.

My invention has for its object the supplementing on an artificial tooth having a single anchoring pin with an additional means which upon becoming embedded in the vulcanite, acts to prevent loosening or displacement by rotation, though relying almost wholly upon the single anchoring pin for retention of the tooth to the plate.

A further object of my invention is to form the pin head and projecting shank, either or both, of rectangular cross section so that the same will constitute a physical shape of a rectangular character which, when embedded in the vulcanite or other body material, will tend to retain the tooth to the denture plate and prevent rotation or looseness.

The additional means which becomes embedded in the vulcanite of the plate and constitutes a part of my improvement is, in its preferred form as a vertical rib extending rearward in a lingual direction and preferably at a distance to the side of the pin so as to leave a space between the said rib and the pin into which the vulcanite of the plate may extend.

My invention will be better understood by reference to the accompanying drawing in which: Fig. 1 is a perspective view of a frontal tooth embodying my invention; Fig. 2 is an elevation of the same, presenting to view the rear or lingual surface thereof; Fig. 3 is a vertical section of an artificial tooth embodying my invention, taken

on line 3—3 of Fig. 2, and with the vulcanite plate indicated in dotted lines; and Fig. 4 is a transverse section of a tooth embodying my invention, taken on line 4—4 of Fig. 2.

2 is the body of the tooth, 3 is its incisal end; 7 is the upper or cervical end, and between the said incisal end and cervical end the rear or lingual part is provided with a vertical surface 4 and a shelf or shoulder 5 located adjacent to the bottom of the said surface 4. 6 represents a single anchoring pin which is rectangular in cross section and shown as provided with a head of usual construction and having its inner end soldered to an anchor embedded in the porcelain body.

In addition to the ledge or shoulder 5, my improved tooth is provided with a vertical rib 8 which extends in a lingual direction from the surface 4 and is preferably of less depth in a lingual direction than is the depth of the shoulder or shelf 5, though its depth may be changed more or less. The governing feature in the depth of the rib 8 lies in the fact that a sufficient space should be permitted between the said rib 8 and the pin 6 in which to receive the vulcanite which makes up the plate and in that manner insure a thorough embedding of the pin and the rib.

In Fig. 3, I have indicated in dotted lines at 10, the plate structure and its relation to the tooth, and it will be seen that this vulcanite plate encloses the cervical end of the tooth and completely embeds the pin 6 and portions 4 and 8 of the tooth structure, and also extends inwardly under the pin and over the shelf or shoulder 5, this latter construction insuring firm and pronounced depression of the porcelain tooth during the incisal movements.

It will also be understood that while the shoulder or shelf 5 is not embedded within the vulcanite but forms a lower bounding portion for the same, the rib 8 does positively project into the vulcanite and, at the same time, is wholly covered thereby and consequently provides an anchoring means in the vulcanite which will prevent movement of the artificial tooth about its anchoring pin 6 as a center. By this means, the artificial tooth is not only thoroughly anchored to the vulcanite plate, but resists any strains which otherwise would cause the tooth to work more or less loose with respect to its attachment to the vulcanite plate.

It will readily be seen that the rib 8 intermediate of the ridge lap of the cervical end 7 and the bite at the incisal end 3 provides a vertical part, out of alignment with the pin, which will definitely engage the vulcanite plate material

10; and this engagement being in close cooperative relation with the horizontal shoulder or shelf 5 which sustains the thrust of the vulcanite plate, provides interlocking of the tooth body 5 and vulcanite along angular lines, with the result that rotating displacement or loosening is impossible. Furthermore, the lingually directed rib or flange parts 8 and 5 provide a socket portion 9 to one side of the pin 6, which is adapted 10 to receive the vulcanite plate material and thereby more effectually interlock the tooth to the plate and prevent relative loosening of the tooth upon the plate.

15 While the rib 8 operates to prevent rotation of the tooth on the plate, the tooth is maintained in the interlocking engagement therewith by the embedment of the head of the pin 6 and also by the overlapping of the collar or neck portion by the vulcanite.

20 A single pin tooth with a rib for engagement within the plate body, as herein described, enables the tooth to be made very small, the size in some cases being such that the anchor pin head is relatively large in respect to the area 25 of the lingual surface 4.

By making the pin 6 of a flattened construction in place of being round as customary in artificial teeth there is greater space 9 provided between the pin and the rib 8 whereby a stronger 30 attachment in the vulcanite plate is provided; and moreover, the flattened or rectangular cross section of the pin insures a more rigid connection with the vulcanite to prevent rotation of the tooth about its pin than where the pins are 35 made circular in cross section, not only during the building up of the denture prior to vulcani-

zation, but also in the finished denture and moreover, even when applying the teeth to the plaster models while positioning them upon the preliminary wax plates of the models.

It will now be apparent that I have devised 80 a novel and useful construction which embodies the features of advantage enumerated as desirable, and while I have in the present instance shown and described the preferred embodiment thereof which has been found in practice to give satisfactory and reliable results, it 85 is to be understood that I do not restrict myself to the details as the same are susceptible of modification in various particulars without departing from the spirit or scope of the invention. 90

Having thus described my invention, what I claim and desire to secure by Letters Patent is:

1. An artificial porcelain tooth having the lingual face of its body made substantially flat with a pin extending therefrom in a lingual direction, said flat face provided with two rib-like portions one of which is formed vertically adjacent one edge of the tooth and the other arranged at right angles thereto, said ribs together forming lateral shielding walls to the pin in a direction vertically and mesio-distally at one side thereof, and wherein also the pin is unobstructed in vertical and mesio-distal directions at its other side.

2. The invention according to claim 1, wherein 105 further, the rib constitutes a ledge which extends to a greater distance from the lingual face than does the vertical rib, and wherein also the pin is flattened and extends to a distance beyond both rib portions.

WINTHROP C. WHITTEMORE.
